UNITED STATES PATENT OFFICE

NICOLAS CROUSET, OF BUENOS AIRES, ARGENTINA

CABINET FOR KEEPING SOUND RECORDS

Application filed January 5, 1931. Serial No. 506,804.

This invention relates to improvements in cabinets for keeping sound records and substantially has for its object to provide a cabinet of the said kind which will include a mechanism combined with an indicator carrying a list of the records contained in the cabinet, in such a way that when shifting the indicator and causing the line of the selected record to come opposite to an index, the respective record may be withdrawn by operating a single button.

Another object of the invention consists in providing a record cabinet arranged in the shape of a desk or other piece of furniture, adapted to support a talking machine, with the indicating device arranged in a convenient position for reading and operating the same.

Another object of the invention is to provide a record cabinet wherein the records will be conveniently kept and protected and automatically wiped or cleaned.

Further objects and advantages of the invention will become apparent in the course of this specification.

In order that the invention may be clearly understood and carried into practice, the same has been shown, by way of example, in the accompanying illustrative drawings, wherein:—

Figure 1 shows a perspective of a sound record cabinet, in accordance with this invention, with the door in its open position.

Figure 2 illustrates a horizontal section of the same.

Figure 3 is a fragmentary vertical section, on the line A—A of Figure 2.

Figure 4 shows a vertical section on the line IV—IV of Figure 2.

Figure 5 is a vertical section on the line V—V of Figure 2.

Figure 6 illustrates a longitudinal section of a cabinet case, indicating the manner of arranging the velvet protecting strips.

In all the said views, the same numbers of reference indicate like or corresponding parts.

The record cabinet in accordance with this invention, which may be constructed of any desired or convenient shape, style and di-

mensions and of any suitable material, consists, in the embodiment shown, of a square wooden case 1, provided with doors 2 at its front and supported by legs 3. The upper part of the case serves as a support of a phonograph, such as 4, but it will be understood that said phonograph might also be formed integral with the cabinet, if so desired. At the front of the case, when the doors are opened, a series of horizontal compartments 5 will be seen, designed for containing the records 6, one in each compartment. The height of the compartments is such that the records may readily slide in and out, but without any looseness. For indicating the compartments still empty and in order to maintain the partition walls in a perfectly level condition, suitable wooden strips or laths 7, of equal thickness to the records, are placed between the partitions.

At the top of the cabinet, to the left of the phonograph, an indicating panel 8 is arranged, adapted to slide within a slot 9 of the top board of the case 1, so as to permit raising or lowering the same by seizing it by an upper handle 10. The panel is provided with a series of horizontal lines 11, at intervals corresponding with those of the compartments, and on each line, the name or title of the respective record is inscribed. When it is desired to remove any particular record, the panel 8 is shifted so that the line 11, bearing the reference to said record, will be placed at the same level with the index 11', affixed to the case 1. In this position, the panel will so operate a mechanism hereinafter to be described, that depressing a single button 12, placed at the right side of the compartments, will cause the desired record to project from its compartment.

The horizontal partition walls 5, constructed of wood, suitably prepared to prevent warping, are of triangular shape and are arranged in a stack to the entire height of the cabinet, the conjoint of them being supported by three metallic rods 13, which extends through holes formed near the corners of the partition walls. On said rods, suitable washers 14 are mounted, between

every two partitions, of a thickness equal to the height of the compartment confined thereby. By means of nuts 15, screwed on the ends of the rods 13, the conjoint may 6 conveniently be adjusted and maintained in the required rigid condition.

The triangular shape of the partitions allows the records 6, even of those having the largest diameter, to protrude beyond the 10 rear sides of the triangle, in order to engage with the two stationary stop laths 16, having for their purpose to limit the entrance of the records into the compartments, and center the same so as to cause them to protrude to an equal extent at the front of the cabinet, along the middle line of the same. Said stop laths are of different widths, so as 15 to adapt themselves to small and large records, as may be seen by referring to Figure 5, in which construction a certain number of the lower compartments are destined to contain large records, while the upper compartments are to hold small records. In 20 this way, records of several sizes are caused 25 to protrude to an even extent at the front side.

The record expelling device includes a series of hammers 17, formed of a small lath of unwarping wood, all mounted on the 30 same vertical shaft 18, with interposition of a corresponding number of washers 19, of a thickness similar to that of the partitions 5. Said hammers are formed with one 35 end narrow and the other wide, for the purpose of using the same hammer for records of two sizes. For small records, the hammer is arranged with its wide end opposite the record, as shown with full lines in Figure 2, while in connection with large records, the narrow end of the hammer faces 40 the record, while the wide end extends in a rearward direction, as indicated by the dot and dash lines in Figure 2. In this arrangement, the part of the hammer which 45 oscillates opposite the expelling device will always assume the same positions, regardless of the size of the records. The ends of the hammers, acted upon by said device, are guided horizontally by a vertical reed 50 20, with a hammer moving within every opening of the same. The object of this arrangement is to maintain the hammers exactly opposite the mechanism. The part of the hammer acting on the record, moves 55 within the end part of the respective compartment, at the free space between the rear of the record 6 and the rod 13.

The expelling device, made integral with the indicating panel, includes a level horizontal piece 21, secured by means of screws to the lower end of the panel and provided with a vertical rectangular slot 22, within which freely slides a vertical guide bar 23, secured at its opposite ends to the lower 60 board 24 and upper board 25, between

which is mounted the conjoint of the compartments and operating device. Said guiding means has for its object to guide the expelling device and the panel in their vertical motion, in cooperation 70 with the slot 9 of the top board of the case 1, being besides provided with a lateral piece 26, formed with notches 27, after the manner of a rack, for retaining the expelling device and the panel in the 75 position selected. To that end, the horizontal piece 21 contains a metallic ball 28, subject to the pressure of a spring 29, which causes the same to enter into one of the notches 27, the pressure exerted being sufficient 80 to prevent the mechanism and panel from descending by their own weight. The distance separating the notches is equal to the interval between the compartments and the hammers, so that the expelling mechanism 85 will always assume a position exactly level with one of the hammers.

The side of the piece 21 opposite to the panel is formed with a dove tail shaped groove 30, into which enters the correspondingly shaped part of a slide 31, adapted to move horizontally in said groove, perpendicularly with regard to the hammer, against which it bears with its end, as 90 shown in Figure 2. The other end of the 95 slide is provided with a stop 32, having connected to it the end of a flexible traction cord 33 which extends into a flexible incompressible tube 34, secured to a part of the piece 21, at a suitable distance from said 100 stop. The free space between said part and the stop 32 is greater than the stroke of the slide in the operative motion of the hammer, so that when pulling the cord 33 in order to move the slide and operate the 105 hammer, said stop 32 will not abut against the afore-mentioned part of the piece 21.

The other end of the cord and of the flexible tube extends into the lever mechanism operated by the control button. The conjoint of the parts forming said mechanism is arranged at the other side of the cabinet and the tube and flexible cord extend to said parts by passing around the rear of the column of partitions 5. To one of the 110 standards 35 of the front frame of the cabinet is secured, to the rear side and at the middle of its height, a suitable bracket with a stud 36, on which is mounted to oscillate the lever 37, jointed at its other 115 end to another lever 38, forming with the former a sort of horizontal pair of pincers. Said pincers are supported by a spring 39, secured to a rear guide 40, the pincers moving against said spring. The other end 120 of the lower lever 38 in turn is jointed by means of a pin 41 to a sliding piece 42, guided for vertical motion in a groove formed in the standard 35. Said piece 42 125 is formed integral with the operating but- 130

ton 12, which extends outside from said standard and has the shape of an elongated handle in the case shown in the drawings. To an intermediate point of the upper lever 5 37 is secured the end of the flexible tube 34 and to the lower lever is attached the cord 33. It will be readily understood that when depressing the button 12, the levers will be caused to separate and pull the cord and 10 said pull, being transmitted to the slide 31, will carry the same backward and thus operate a hammer.

In order to prevent the hammers from deviating with regard to the records and 15 inserting between these latter and the partitions 5, the edge of the hammer which engages with the record, is formed with a groove, as indicated at 43 in Figure 5.

A particular advantage of the invention 20 consists in the lining of velvet applied to the compartments, which will protect the records against damage by friction and at the same time automatically wipe the same. In order to avoid the use of an excessive amount of 25 lining material, several strips of velvet are conveniently arranged in suitable parts of the compartments, so as to prevent the records from coming into contact with the wooden walls of the same. To the front 30 edge of the compartments, a narrow strip of velvet 44 is also cemented, so as to extend along the upper and lower side of the partitions. Another strip 45 is longitudinally attached along the middle line of each partition 5 and after passing through a slot 46 formed at about an inch from the front edge 35 of the partition, is cemented to the upper and lower side of the same. Parallel with the rear sides of the partitions, two similar 40 strips 47 are applied, which also pass through similar slots 48 and are cemented to the upper and lower side of the partition, as the strip 45. By thus arranging the velvet strips, the record when entering into the 45 compartment, will not strike against the edge of any strip and gradually cause its separation. As the dimensions of the compartments are such that the record when entering will exert a slight pressure on the 50 velvet, the same will be submitted to a wiping or cleaning action whenever the record is introduced or removed, thereby dispensing with the necessity of specially performing said wiping operations.

55 The operation of the device above described will be readily understood. Since the spaces between the lines of the panel or indicating device correspond with those formed by the compartments, it will be evident that a particular line of the panel will always correspond with the same compartment and that the hammer operating device will be situated exactly in front of the hammer pertaining to the compartment whose 60 line on the panel will at that time be at the

same level with the indicator 11'. Therefore, in order to remove a record, it will be sufficient to place the line bearing the title of the desired record opposite to said indicator and then depress the button or handle 12, 70 whereby the slide 31 will be caused to push the hammer of the corresponding compartment, which in turn will project the respective record a suitable distance to allow conveniently seizing the same. Since all the records protrude a small distance from their compartments, the corresponding empty compartment will be readily found when it is desired to replace the record. In order 75 that there may be no confusion with the compartments not containing any records, small wooden laths 7 are placed in the same, so as to project beyond their front edge, to the same distance as would do a record.

It should be understood that the arrangement is not limited to the embodiment shown; thus, the compartments might be arranged vertically and the panel be placed at another suitable part of the cabinet; further, instead of a flexible cord, another convenient or desired means of transmission might be used.

It will further be evident that several modifications of other constructional details might be introduced, without departing from the scope of the invention, to be particularly set forth in the following claims.

Having now particularly described and ascertained the nature of my said invention and in what manner the same is to be performed, I declare that what I claim and desire to secure by Letters Patent, is:—

1. An improved cabinet for keeping sound records, comprising a series of individual compartments for holding the records; a record expeller for each compartment which operates to expel the record; an operating button; a mechanism operated by said button to operate any one of the expellers; means controlled by the button for actuating the mechanism; an indicating panel for registering thereon, line by line, the titles or headings of the records contained in the compartments, said panel being adapted to slide adjacent to a fixed index; said mechanism being movable with the panel so that the mechanism will be stopped opposite to the expeller corresponding to the compartment whose record is registered on the line of the indicator situated at the index.

2. An improved cabinet for keeping sound records in accordance with claim 1, in which the mechanism comprises a support integral with the indicating panel, said support carrying a guide piece within which moves a member operated by the operating button.

3. An improved cabinet for keeping sound records in accordance with claim 1, in which the record expeller consists of an oscillatory hammer, one end of which engages with the

record and the other with the mechanism acted upon by the operating button, one end of the hammer being narrower than the other.

5. An improved cabinet for keeping sound records in accordance with claim 1, wherein the operating button is arranged to act on a traction cord within a flexible tube of varying length, said cord acting on the mechanism operating the record expelling device.

10. An improved cabinet for keeping sound records in accordance with claim 1, in which the series of compartments consists of a stack of horizontal thin boards, separated at 15 their corners by distances equal to the thickness of the records, the expellers being formed of laths of a thickness equal to that of a record, which also are mounted to oscillate on a shaft, with interposition of washers of a thickness equal to the partitions between the compartments, said expellers entering freely into the rear parts of the compartments, to engage with the rear edges 20 of the records.

25. An improved cabinet for keeping sound records in accordance with claim 1, in which the height of the compartments is equal to the thickness of the records, and the partitions between the same are lined with velvet, 30 plush or similar material, the lining consisting of a strip cemented to the front edge and to the upper and lower side of each of the partitions, and of a longitudinal strip passing through a slot arranged near the front 35 end in said partitions and extending rearward from the same, being secured to the upper and lower sides of said partitions.

7. An improved cabinet for keeping sound records in accordance with claim 1, in which 40 the partition walls of the compartments are of triangular shape, with one of their sides parallel with the front of the cabinet, so that the records, when housed therein, will protrude beyond the rear and bear against 45 two abutments arranged transversely to the stack of partitions near the rear sides of the same, so as to cause the records to protrude beyond their front sides to an even amount.

In testimony whereof I affix my signature.

50 NICOLAS CROUSET.
